UNITED STATES PATENT OFFICE

169,145

TYPEWRITER

John F. Kloski, Windsor, Conn., assignor to Royal
Typewriter Company, Inc., New York, N. Y., a
corporation of New York

Application April 29, 1952, Serial No. 19,515

Term of patent 14 years

(Cl. D64—11)

To all whom it may concern:

Be it known that I, John F. Kloski, a citizen of the United States, residing at 1096 Windsor Avenue, Windsor, county of Hartford, State of Connecticut, have invented a new, original, and ornamental Design for a Typewriter, of which the following is a specification, reference being had to the accompanying drawing, forming a part hereof.

Figure 1 is a perspective view of a typewriter embodying my new design, illustrating the top front and one side of the typewriter, and

Figure 2 is a perspective view illustrating the top back and opposite side of the typewriter.

I claim:

The ornamental design for a typewriter, as shown.

JOHN F. KLOSKI.
